The Clerk shall report to the Board and Patent and make in front of the same a copy of the specification in the words of the said inventor, containing the improvements in the mode of turning flat iron on Rail Roads for which the said Patent was granted, dated the twenty-third day of August, 1831, which he has taken, being fully cancelled on account of a defective Specification.

in all where the present shall come. Be it known that I, James Thompson of the city and County of Baltimore and State of Maryland have invented a novel and useful improvement in the mode of running short cars upon rail roads with car and carriage particularly of those round the curve of streets whereof are used that the following is a full and exact description of said in-vention or improvement as invented or improved by me viz. And to apply the common principles of the flanchises of the flanchises of the streets for the purpose, for passing the following manner. That a flat rail, such however may be ground if required at the commencement of the curve and in a position to be contact-ed by under the flanchises of the aforesaid rail upon the outer track of the circle so that no other part of the wheel which is upon the outer track of the circle shall touch or be upon the rail but the flanchises of the flanchises they bearing the wheel straight of the road and running while the opposite wheel which is upon the inner track of the circle are to be over and bear upon them tandem in the usual way and their flanchises straight in a row or otherwise which tandem are as dimly as possible to be seen in diameter before the periphery of the flanchises. While the bear-ing surfaces of the wheels which are in contact with the rail is held straight by the car and moved by straight lines from every point there should thus be formed the greatest of the curve of the wheel and two angles to the curve, one of but one angle and the other, there but one even, which stands, so the said improvement, this operation will of the wheel ^{are} thirty, and when the car and carriage are combined about these points in such a position of about ^{one} third of the circumference of the rail, the difference in distance between the flanchises and head before the car, the head of the rail and the tail

coupling as stated would cause a curve of a somewhat smaller radius of the arches were not confined to the carriage in a parallel position with each other but this being generally done necessary the wheels run upon lines of tangents and lines upon the inner track being as wide apart as the coupling is the wheels come keep constantly encroaching the carriage outward and this cause the carriage to tend to run upon a larger circle than the difference in diameter of the track and flanges would otherwise give but the depth of the flanges and couplings may be so made as to have any other radius of a circle desired. What follows may be my invention or improvement is the application of the flanges of the track on one side of each road carriage and of the track of the wheels on the other side, to turn curves upon all ways particularly such as turn upon the corner of the street, when in use in cities and convenience of turning up on the principle herein set forth.
